MASK FOR AVIATION OR CLINICAL PURPOSES

Arthur H. Bubulian, Rochester, Minn.

Application October 18, 1941, Serial No. 415,536

2 Claims. (Cl. 128—146)

My invention relates to self-sealing masks for aviation or clinical purposes, and has for its object to provide a mask structure for application to the face of a wearer to form a breathing chamber sealed from outside atmosphere wherein special means are provided for sealing the mask at the sides of the nose where the same form the angle with the face.

Masks have been developed for both clinical and aviation purposes to be worn over the face, which are so shaped that a breathing chamber is formed between the face and the body of the mask. Such a breathing chamber may enclose both the mouth and nose or the nose only. The masks are ordinarily made of semi-rigid material, such as vulcanized rubber. For such masks ordinarily oxygen is delivered to the breathing chamber and it is important to have complete sealing of the margins of the mask upon the face of the wearer. In this connection a serious difficulty has been encountered in producing a full sealing at the sides of the nose adjacent the point where the sharp angle occurs between the sides of the nose and the body of the face. Because of the fact that no two people have quite the same angle of incidence at that point and because the substance of the mask permits spreading over the nose it has been found that quite frequently there is not effective sealing at that point with the result that there is leakage of oxygen and exhalation gases out and of the outside atmosphere in.

I have discovered that if a metal clamping device is anchored upon the nose-enclosing portion of the mask itself, preferably by being imbedded in the body of material making up the mask, with inwardly disposed spring arms extending toward the edge of the nose-receiving part of the mask at the sides and toward the angular junction of the side walls of the nose and the cheeks, it will certainly seat the mask body into that angle to produce effective and complete sealing with any type of face.

It is a principal object of my invention, therefore, to provide a mask structure wherein there are anchored directly upon the top of the nose-receiving part of the mask and extending from that point along the sides of the nose-receiving portion, and toward the edge of the mask a pair of spring arms adapted to cause the mask body to move inwardly to produce a gripping of the sides of the nose at the angle of junction with the face and so to effect sealing thereof.

It is a further object of my invention to form the anchoring means as an arch-like body over

5 the nose-receiving portion of the mask at a point somewhat inwardly from the margins thereof, and to have connected with the ends of said arch a pair of spring members adapted to cause the mask body to engage the sides of the nose at the junction angle thereof with the adjacent parts of the face.

10 It is a further object of my invention to provide off-set fingers to the spring arms aforesaid such that the ends of said fingers will tend to force the mask body against the sides of the nose at the points of junction with the adjacent parts of the face.

15 It is a further object of my invention to imbed the spring means aforesaid in the substance making up the body of the mask.

20 It is a further object of my invention to provide adjacent the margins of the mask and particularly along the margins of the nose-receiving portion thereof an inwardly turned feather-edged flap, in combination with said arms and fingers so that when the mask is worn said flap will be forced against the sides of the nose at the points of juncture with the adjacent parts of the face.

25 The full objects and advantages of my invention will appear hereinafter in the description thereof in the following specification, and the features of novelty by which the advantageous results above outlined are secured will be particularly pointed out in the claims.

In the drawing illustrating an application of my invention in one of its forms:

30 Fig. 1 is a semi-perspective plan view showing the position of the parts as they would be when applied to a face.

35 Fig. 2 is a fragmentary plan view looking directly down upon the mask body.

40 Fig. 3 is a similar view of the spring metal member shown in Figs. 1 and 2 as imbedded in the material of which the mask is composed.

45 Fig. 4 is a view of a part of the mask embodying my improvement looking toward the edge of the nose-receiving part thereof and showing the position of the parts before the mask has been applied to a wearer's face.

50 Fig. 5 is a reverse part sectional view of the nose-receiving portion of the mask as it will appear when worn.

Fig. 6 is a perspective view of the spring metal member adapted to be attached to the nose-receiving part of the mask.

Fig. 7 is a sectional elevation view taken on line 7—7 of Fig. 2.

As illustrated, any type of mask 10, which has

a breathing chamber 11 adapted to be formed by application of the mask to the face of a wearer, may have a breathing outlet 12 and will have a nose-enclosing portion 13. About the inner margins of the mask body, and particularly of the nose-enclosing portion 13, I provide a rearwardly turned feather-edged lip 14, as shown in Fig. 4. This lip normally will engage the face of the wearer when the mask is worn and is compressed against the sides of the nose at the point of junction with other parts of the face by my improved spring means which I will now describe.

As shown in detail in Figs. 3 and 6, this spring means, which may be formed of piano wire or other suitable spring metal, is provided with an arched portion 15 which goes directly over and is secured to the nose-receiving portion of the mask in a position to extend transversely about and toward the end of the nose when the mask is worn. At the corners 16 and 17 of this arched portion a pair of spring arms 18 and 19 extend along the sides and close to the margins, the face contacting portions of the mask having an inward curve as indicated at 20 of Fig. 3. At the ends of the spring arms 18 and 19 are pressure fingers 21 and 22 formed of the wire bent back upon itself and having a shape, as shown in Figs. 6 and 7.

Although it is within the scope of my invention and intended by me to secure the spring member 15, 16, 17, 18, 19, 21 and 22 to the nose-receiving portion of the mask either outside or inside of it by any suitable securing means, I have found it convenient and preferable to secure it by means of casting it directly into the body of rubber or other material of which the mask is composed. As best shown at 23 of Fig. 7, also as shown in Figs. 1, 2, 4 and 5, the parts of the spring member protruding the mask material in which it is encased are designated 15', 16', 17', 18', 19', 21' and 22' it being understood that the parts of the spring member designated by the corresponding unprimed numbers

are present within the body of mask material as shown and designated.

The advantages of my invention will be apparent from the foregoing description. Fundamentally the improvement above defined produces effective and certain sealing of the breathing chamber at the one point where such sealing, particularly with masks made of vulcanized rubber, has been not only difficult but often impossible of accomplishment. The metal clamping device is so incorporated with the organization of the mask body itself that it does not detract from the appearance of the mask body, has no parts exposed or in position to interfere with the use of the mask, whatever form of mask is employed, and finally is always dependable and certain to perform the sealing function intended of it.

I claim:

1. In a mask structure having a nose-enclosing portion, a spring member provided with an arch portion secured to said nose-enclosing portion in a position to extend transversely about and toward the end of the nose when the mask is worn, and having spring arms connected with the ends of said arch and extending toward the margins of the nose-enclosing portion, and an angularly disposed finger portion on the end of each arm, the arms and finger portions acting to cause the mask body to seat against the sides of the nose at the junction thereof with adjacent face portions.

2. In a mask structure having a nose-enclosing portion, spring means secured to said nose-enclosing portion in a position to extend transversely about and toward the end of the nose when the mask is worn, said spring means including spring arms extending towards each other along the sides of said nose-enclosing portion and having their ends at points close to the nose-contacting edge of the mask, all parts of said spring means being held in position by being embedded in the body of said nose-enclosing portion.

ARTHUR H. BULBULIAN.
